(57) CLAIM

The ornamental design for a handle for pullup exercise bar, as shown and described.

DESCRIPTION

FIG. 1 is a perspective view of an exemplary embodiment of a handle for pullup exercise bar showing our new design.

FIG. 2 is a front elevational view thereof.

FIG. 3 is a right side elevational view thereof, the left side elevational view being a mirror image of the right side elevational view and therefore not illustrated.

FIG. 4 is a top plan view thereof; and,

FIG. 5 is a bottom plan view thereof.
